Patented Feb. 17, 1914.

UNITED STATES PATENT OFFICE.

EDWARD E. GOLD, OF NEW YORK, N. Y., ASSIGNOR TO GOLD CAR HEATING & LIGHTING COMPANY, OF NEW YORK, N. Y., A CORPORATION OF NEW YORK.

AUTOMATIC CONTROLLING DEVICE FOR HEATING APPARATUS.

1,087,231.

Specification of Letters Patent.

Patented Feb. 17, 1914.

Application filed January 29, 1913. Serial No. 744,823.

To all whom it may concern:

Be it known that I, EDWARD E. GOLD, a citizen of the United States, residing in the borough of Manhattan, city, county, and State of New York, have invented certain new and useful Improvements in Automatic Controlling Devices for Heating Apparatus, of which the following is a specification.

My invention relates to heating systems and will be found particularly useful in connection with car heating systems, and is shown as adapted for use in connection with a steam car heating system.

The invention consists in the provision of means for automatically controlling the supply of heating fluid to the heating apparatus by the temperature of the apartment to be heated.

The invention also consists in details of improvement in the particular controlling devices employed.

A desirable form in which my invention may be embodied is illustrated in the accompanying drawing, wherein—

Figure 1 illustrates a perspective view of a portion of a railroad car having my invention applied thereto. Fig. 2 is a face view partly broken of an electric heater employed by me. Fig. 3 is a vertical section of the admission valve and its controlling devices. Fig. 4 is a face view of a thermostatically-controlled switch located in the apartment to be heated. Fig. 5 is a view similar to Fig. 4, parts being removed, and Fig. 6 is a vertical section on the line 6—6, Fig. 4. Fig. 7 is a side elevation of the parts illustrated in Fig. 4.

According to my invention the temperature of the apartment to be heated controls the supply of heating fluid to the radiating means through a thermostat located in the said apartment, which is in an electric circuit. In this circuit is an electric heater and when the temperature of the apartment rises to the proper point the electric heater is energized and through thermostatic-controlling means located near the heater the admission valve controlling the supply of heating fluid to the radiator is closed.

In the particular construction illustrated in the drawings a steam heating system is shown wherein steam is taken from the train-pipe A through supply-pipe B which extends through double car floor X to radiator C, the lower branch of which leads to a

return pipe D, the return pipe D leading to an outlet E, and this outlet may well be of the usual type wherein a thermostatically-controlled outlet valve is located within a casing F, and controls the escape of the condensed water from the system in the usual manner. As this forms no part of my invention it has not been illustrated. The supply pipe may be provided with a hand valve b if desired.

Within the casing G is located an admission valve H for controlling the supply of heating fluid to the radiator C. This admission valve is automatically operated by devices which are controlled by the temperature within the apartment, and my invention is related to the means for causing such automatic operation. The admission valve H is directly controlled by a thermal motor, which as illustrated is in the form of an expandable vessel I partly filled with a volatile fluid which causes the vessel to expand upon an increase in temperature, and this vessel is caused to be expanded by an electric heater J when the same is energized. The said electric heater is in an electric circuit composed of wires K, L. The wires L lead to a source of electricity, and wires K connect the electric heater with the means whereby the same is automatically put in circuit and energized when the temperature in the car reaches a desired point. Said automatic controlling means are illustrated in section in Fig. 6 and comprise a thermostat M consisting of an expandable vessel partly filled with a volatile fluid and adapted upon expansion to operate a switch N so as to close the circuit and cause the heater J to be energized, whereupon the expandable vessel I closes the admission valve H and shuts off the supply of heating fluid to the radiator.

I have provided an improved form of switch which is operated by the thermostat M and the same comprises a magnetic switch-member n and magnetized contact points n¹, n². The switch proper n is mounted in adjustable needle point bearings n³ and has a projecting rear end carrying two rods n⁴, between which is received the operating end n⁵ of a bell-crank lever n⁶ which is pivotally mounted in the frame. A set-screw n⁷ adjusts the arm n⁵ of the bell-crank lever with the arm n⁸. A frame O is provided for holding the said switch-member, and this frame comprises a rear plate o and

a front plate o^1 ; lugs o, o^3 are attached to the rear and front plates respectively through which bolts $o^4 o^5$ are passed to hold the device together and to support vessel M through clips o^2 .

Means are provided for assisting the contraction of the thermostat M comprising a spring P shown in dotted lines in Fig. 5, and this member will engage the walls of the thermostat through a small plate p . The expansion of the thermostat M will engage the rear arm n^8 of the pivoted bell-crank lever causing its opposite arm n^5 to move the rear end of the switch-member n in the direction 15 of movement of the expansible vessel, and causing its front or contacting end to move in the opposite direction and make contact with the contact point n^1 . The battery wire L is connected to the frame O , as illustrated, 20 and the frame is in electrical contact with the switch-member n , wherefore the movement of the said switch-member n to contact n^1 will close the circuit and cause the heater J to be energized. Upon the temperature of 25 the car falling the thermostat M will contract, its movement in this direction being assisted by the spring P , and thereupon a spring n^9 , Fig. 6, pressing upon the arm n^5 of the bell-crank lever, will move the switch-member n out of contact with the terminal n^1 , (thereby breaking the circuit) and into contact with the contact n^2 .

Both contacts n^1 and n^2 are permanent magnets for the purpose of holding the switch member n which is also a magnetic metal plate, preferably of spring metal, so that said parts will be held together obviating sparking. The employment of the spring switch-member together with the use 40 of the permanent magnets as contact points causes a very quick separation of the contact points and to a large extent overcomes the formation of an arc.

The wire K is provided with a hand-45 switch k by which the circuit may, if desired, be broken. This wire K and the battery wire L are connected to the heater J by binding posts k^1, l which are mounted in the rear plate j of the said heater.

The electric heater J may be of any desired construction. As illustrated it has a back plate j which has a rear radiating face which is substantially flat as illustrated and may be provided with any desired type of 55 electric heater. As illustrated heating wires j^1 are surrounded by insulating enamel j^2 . A frame Q supports the valve together with the expansible vessel I and the heater J , and the heater is mounted in a ring q , which 60 ring has a flange q^1 whereby it also supports the vessel I . The parts are held in position by swing bolts q^2 .

The expansible vessel I has a rear wall i which is normally substantially flat and 65 when the vessel is contracted, as illustrated

in full lines in Fig. 3, is adapted to lie against a flat, radiating face of the back plate j of the heater so as to be in contact therewith throughout substantially the whole of said vessel. Thereby the greatest 70 heating efficiency is obtained. When the vessel I is heated and expanded it will pass to the position shown in dotted lines in Fig. 3, wherein its rear wall i has passed substantially out of contact with the heater; at least 75 only a small part thereof at the center remains in contact with the heater. Thereby the ventilation of the vessel is obtained and it is adapted to cool much quicker than would otherwise be the case, and is rendered 80 more energetic in action.

The valve H is provided with a stem h upon which is a head h^1 which receives the thrust of the vessel I . This valve is normally held open by a spring h^2 which lies 85 between the flange h^3 on the valve and the valve seat h^4 . A gland h^5 prevents the leakage of steam around the valve stem.

In many particulars the apparatus herein shown is illustrative only and may be modified, as for instance, the employment of a steam heating system is not essential to my invention, nor is it essential that the automatically-controlled valve should be situated in a supply pipe, as my invention could 90 equally well be applied to the automatic control of an outlet valve in the return pipe. Nor is my invention concerned with the particular type of electric heater employed. It will therefore be seen that numerous changes 95 may be made in the construction of my invention and equivalent devices employed within the limits of the appended claims.

I claim as my invention:—

1. A heating system comprising a supply 105 pipe, a radiator, a valve for governing the supply of heating fluid to said radiator, and means for automatically controlling said valve by the temperature of the apartment to be heated, comprising a thermostat located in said apartment, an electric circuit in which said thermostat is included, and which is adapted to be closed thereby, an electric heater in said circuit, having a substantially flat radiating surface, a thermal 110 motor located near said heater and adapted to be operated as said heater is energized, said motor adapted to lie in substantial contact with said heater when said heater is out of circuit and to draw away therefrom 115 when heated by said heater, and means controlled by said motor for closing said valve.

2. A heating system comprising a supply pipe, a radiator, a valve for governing the supply of heating fluid to said radiator 120 and means for automatically controlling said valve by the temperature of the apartment to be heated, comprising a thermostat located in said apartment, an electric circuit, in which said thermostat is included and 125

which is adapted to be closed by said thermostat, an electric heater in said circuit, and an expansible vessel located adjacent said electric heater and containing a volatile fluid, 5 said expansible vessel having its wall next said heater adapted to be substantially parallel therewith when said vessel is contracted whereby said vessel is in favorable position to absorb heat radiated from said heater, 10 said apartment thermostat adapted to close said circuit upon a variation in the temperature in said apartment, and said vessel adapted when expanded to form a substantial space between it and said heater whereby 15 by said vessel may be ventilated, and a connection between said admission valve and said vessel, whereby the expansion of said vessel will close said valve.

3. A car heating system, comprising a 20 radiator and means for supplying heating fluid thereto, an admission valve for governing such supply, and means for automatically controlling said admission valve by the temperature of the car, comprising a thermostat 25 located in said car, and an electric circuit, and means for closing said circuit by said thermostat, comprising a magnetized metallic switch member and means whereby the same is moved as said thermostat operates, and magnetic contact points for said 30 switch, an electric heater in said circuit, and means adapted to be affected by said heater when in circuit for closing said admission valve.

35 4. A car heating system, comprising a radiator and means for supplying heating fluid thereto, an admission valve for governing such supply and means for automatically controlling said admission valve by the 40 temperature of the car, comprising a thermostat located in said car, and an electric circuit, and means for closing said circuit by said thermostat, comprising a magnetized metallic spring switch member, and means whereby the same is moved as said thermostat 45 operates, and magnetic contact points for said switch, an electric heater in said circuit, and means adapted to be affected by said heater when in circuit for closing said 50 admission valve.

5. A steam car heating system comprising

a supply pipe, a radiator, an admission valve in said supply pipe, and means for automatically controlling said valve by the temperature in the car comprising a thermostat 55 consisting of an expansible vessel located in said car containing a volatile fluid, and operated by variations in the temperature in the car, an electric circuit and means for closing said circuit by said thermostat comprising a movable magnetized, metallic, 60 spring switch member adapted to be moved by the expansion of the thermostat and magnetic contact points for said switch, an electric heater in said circuit, an expansible vessel located adjacent said electric heater, and adapted to lie close to said heater when contracted and to move away on expansion, and a stem on said admission valve located near said last-named expansion vessel, whereby 65 the said vessel is adapted to close said valve. 70

6. In a heating system, valve-controlling means including in combination a heater having a substantially flat radiating portion, an expansible vessel adapted to contain 75 a volatile fluid, and having a wall adapted to be substantially in contact with said radiating portion when the vessel is contracted and upon expansion thereof to cause a substantial part of said wall to pass out of contact with said radiating portion.

7. In a heating system, automatic temperature-controlled devices comprising an expansible vessel having volatile fluid therein and affected by the temperature of the 85 apartment to be heated, a movable magnetic switch member adjacent said vessel, magnetized contact points adapted to retain said switch member in either position to which it is moved by said expansible vessel, 90 an electric heater, an electric circuit including said switch and heater, a thermal motor adjacent said heater, a supply pipe, a valve therein, and means whereby said valve is controlled by said motor.

In witness whereof, I have hereunto signed my name in the presence of two subscribing witnesses.

EDWARD E. GOLD.
